His Attorney.

UNITED STATES PATENT OFFICE.

EUGENE F. INGLES, OF CHICAGO, ILLINOIS.

AUTOMATIC AIR-REGULATING DEVICE FOR GASOLINE ENGINES.

1,408,353.

Specification of Letters Patent. Patented Feb. 28, 1922.

Application filed June 25, 1919. Serial No. 306,754.

To all whom it may concern:

Be it known that I, EUGENE F. INGLES, a citizen of the United States, residing at the city of Chicago, in the county of Cook and State of Illinois, have invented certain new and useful Improvements in Automatic Air-Regulating Devices for Gasoline Engines, of which the following is a specification.

My invention relates to means for automatically regulating the amount of air supplied to the explosive mixture which is injected or sucked into the explosion chamber in explosive engines and the like, and my invention is specially designed to automatically furnish the correct amount of air to the explosive mixture to provide the highest explosive efficiency in the explosion chamber at all speeds.

Another object of my said invention is to provide means for admitting cold air into said mixture, when the admission of such cold air will increase the efficiency of such explosive mixture.

Another object of my said invention, is to provide means for admitting steam or moist vapor into said explosive mixture whenever the admission of such steam or moist vapor will increase the explosive efficiency of said mixture.

In most internal combustion engines, the gasoline is sucked into the explosive chamber by the vacuum created by the withdrawal of the piston from the head of the cylinder. It will be apparent that the suction is the lowest when the engine is running at the slowest speed, and that the suction increases as the speed increases. Thus it will be seen that the increased suction draws into the explosion chamber the increased amount of gasoline required as the speed of the engine increases. As the amount of air admitted to the explosive mixture should be kept at a uniform proportion to the gasoline content, it will be apparent that the amount of air should be increased as the amount of explosive gasoline content is increased. It will also be apparent, that if the size of the air intake is adjusted to provide a suitable volume of air for the engine when running at its lowest speed, that such air intake will be too small to supply the air required when said engine is running at its highest speed; also, if the size of the air intake opening is properly adjusted to supply the amount of air required when the engine is running at its highest speed, it

will supply too much air, when the engine is running at its slowest speed. To overcome these difficulties, means have heretofore been provided for opening and closing the air intake by some means operated by hand of the operator. While these means do fairly well on all stationary engines, and marine engines, where the speed is kept at a uniform rate after one regulating, they are of very imperfect control when employed on automobiles, where the speed is being continuously changed to conform to the speed of traffic or the conditions of the road, and it is usual to see engines attaining not more than half their efficiency, and often emitting a dense cloud of smoke due to poor combustion through lack of a properly regulated explosive mixture. By the special construction employed in my said invention, the engine automatically selects the amount of air required to provide the most suitable mixture at all speeds, and requires no thought or attention of the operator, and secures to the engine the highest efficiency, without waste or loss from too rich a mixture.

I attain these objects, and the other objects hereinafter more particularly set forth, by means of the special construction shown in the accompanying drawings, in which—

Figure 1 shows a section view of my said device.

Figure 2 shows a plan view of the valve seat and air passage.

Figure 3 shows a section view of the conduit, on line 1—1 of Fig. 1.

Figure 4 shows the valve and port for admitting cold air to the conduit.

In the accompanying drawings, in which like numerals of reference refer to similar parts throughout said drawings, 1 represents a suitable conduit for conducting the air from the air manifold to the air intake of the engine. It is provided at the end 2 with suitable shape for convenient attachment to the air manifold, and at the end 3 it is suitably shaped for connection to the air intake of the engine. I have preferably made this conduit substantially rectangular in cross-section, as shown in Figure 3, with a rectangular by-pass around the valve at 16. Within the conduit 1 I have provided the valve seat 4, with the port 5 therein. This valve seat is preferably formed at an angle to the perpendicular, as shown, and of the peculiar shape as shown, with a rounded

port below, and a smaller port above, connected by a narrower passage having parallel sides 5^a to provide a guideway and support for the valve 6 mounted therein. The 5 port 5 consists of a circular lower portion, a narrow upper connecting portion and an upper reduced circular portion communicates with the by-pass 16, and the valve seat 4 extends around the lower circular portion 10 of the port 5 and terminates at opposite sides of the narrow passage as clearly shown in Figure 2 of the drawing. An upper seat portion 4^a is provided at the said upper reduced circular portion of the port to co- 15 operate with the upper portion of the valve. The side walls of the conduit form circular enlargements or crimps at the said narrow upper connecting portion of the port and the said portions or enlargements reinforce 20 the conduit at the pivot of the valve. The valve 6 is constructed with a lower portion 7, suitably weighted, and of suitable size and shape to properly cover the lower portion of the port 5, when said valve is at rest upon 25 said valve seat and port. The upper portion of the valve at 8 is also preferably made of a suitable size and shape to cover the upper portion of the port 5 when said valve is at rest upon the valve seat of said port. At 9 30 the neck of said valve is adapted to fit the narrowed portion of the port 5 and move backward and forward therein, and be guided thereby that it may more accurately adjust itself to the surface of the valve seat. 35 A pin 10 is provided in the walls of the conduit 1, which passes through the valve at 11, and upon which the said valve rotates backward and forward in its operation. At 12 I have provided a cold air port in the conduit 40 1, with the valve 13 adjustably mounted to cover all or a portion of said port, as desired in operation. At 14 I have provided a connection for admitting steam or moist vapor to the conduit, when desired, and the valve 45 15 for opening and closing said opening as desired in operation. This connection is suited for connection with any suitable source of steam or moist vapor supply (not shown) by means of a flexible hose or pipe. 50 As ordinarily constructed, the by-pass 16 is made of suitable size to supply the required amount of air for the engine in starting, and while running at its slowest speed, without opening the valve 6. In usual operation, the port 12 is closed, and the steam connection 14 is also closed. The valve 6 rests upon the valve seat, closing the port 5 when the engine is at rest. When the engine is started, the amount of air required 55 for the mixture enters the air intake by means of the by-pass and around the port and valve in the conduit. Whenever the speed of engine exceeds that at which the by-pass will furnish a sufficient amount of 60 air for the mixture, the suction from the

engine overcomes the weight of the valve 6 and lifts it more or less from its seat, admitting more or less air, as it is raised higher, or lowered. It will be apparent, that the faster the engine runs, the greater will be 70 the suction against the valve, and wider it will be opened, to admit the greater amount of air required for the engine at the higher speed. It will also be apparent that as soon as the speed of the engine is reduced, the weight of the valve will lower it to the position where the suction of the engine just counterbalances its weight. Thus, automatically, the valve opens or closes in harmony with the higher or lower speed of the 75 engine, thereby regulating the amount of air admitted to conform to the speed and mixture required by the engine. It will also be seen that my device operates entirely by gravity, and that there are no springs, or 80 other delicate or intricate parts liable to get out of order or become injured or displaced in operation.

Whenever the conditions of the atmosphere or weather are such that the admission of cold air into the explosive mixture will increase its explosive efficiency, the valve 13 is opened more or less, as desired, to admit the desirable amount of cold air into the conduit and air intake. 90

Also, whenever the conditions of the air, or weather are such that the introduction of moist vapor, or steam into the explosive mixture will increase its explosive value, the valve 15 is opened, and steam or moist vapor 100 from said connection is introduced into the conduit and air intake, as desired. 95

Having thus described my invention, I claim:

1. In an air regulating device for gasoline engines, the combination of an air conduit connected with the intake manifold; a double valve seat in said conduit; a port in said valve seat; a pivotally mounted valve adjacent said valve seat; a by-pass around 105 said valve seat substantially as shown and described.

2. In an air regulating device for gasoline engines, the combination of an air conduit connected with the intake manifold; a double 115 valve seat within said conduit having a narrow guideway between the seats having plane side walls; a double valve pivotally mounted in said guideway adjacent said valve seats; a by-pass around said valve seats, all substantially as shown and for the purposes described. 120

3. An air regulating device for gasoline engines, comprising an air conduit connecting with a manifold; a double valve seat in 125 said conduit inclined at an angle to the perpendicular with a narrow guideway therebetween; a double valve pivotally mounted in said guideway and adapted to normally engage said valve seats to close the ports; a 130

by-pass around said valve seat, all substantially as shown, and for the purposes described.

4. An air regulating device for gasoline engines comprising an air conduit; a double valve seat in said conduit with a narrow guideway between the separate seats; an offset chamber in said conduit adjacent said valve seats forming a by-pass around said 10 seats; a double valve pivotally mounted in the guideway and adapted to normally engage said valve seats and to close the ports, all substantially as shown and for the purposes described.

15 5. An air regulating device for gasoline engines, comprising an air conduit; a double valve seat having a double port therein, the two seats being connected by a narrow passage forming a guideway; a rectangular offset chamber in said conduit adjacent said valve seat and forming a supplemental air passage around said seats and a weighted double valve mounted adjacent said seats in the chamber in the guideway therebetween 20 and adapted to be guided thereby during 25

opening and closing of the seats substantially as shown and described.

6. An air regulating device for gasoline engines, comprising an air conduit; a double valve seat having a double port connected 30 by a narrow guideway; a rectangular offset chamber in said conduit adjacent said valve seat and forming a supplemental air passage around said seat; a weighted double valve mounted adjacent said seat in said chamber 35 in the annular guideway and adapted to be guided thereby during opening and closing; a separate port for admitting cold air and a valve for closing said port; a third opening for admitting steam to said conduit, and 40 a valve for opening and closing said opening, all substantially as shown and described.

In testimony whereof, I have hereunto affixed my signature at the city of Chicago, county of Cook and State of Illinois, in the 45 presence of two witnesses.

EUGENE F. INGLES.
